ABSTRACT OF THE DISCLOSURE

A new electro-mechanical loader's safety switch whereby a manually operated lever is rotated and latched in a position wherein the lever causes an electric switch to be closed to complete part of a gun firing electric circuit. The latching means releases the lever either automatically upon recoil of the breech or by manual operation. A pin on the lever moves in an arcuate path to intercept a trip link carried by a slide link which cooperates with the reciprocating motion of the breech.

This invention relates to guns and more particularly to guns carried in vehicles utilizing a man for loading and another man for firing, wherein the loader is provided with an electric switch to disarm the gun. The novel loader's safety switch is particularly adapted to self leveling 105 mm. guns, or the like, carried by tanks wherein the tank and loader often are moved violently relative to the gun when traveling over rough ground.

Heretofore the electric circuit that is closed by the gunner to fire the gun included, in series, a manually operated switch placed near the loader. After the gun was fired the loader would manually open the switch, load the gun, and then manually close the switch when he had reached a position of safety. This device was not satisfactory because the loader often neglected to open the switch.

This invention provides an electro-mechanical apparatus in combination with a gun that requires the gun loader to close an electric contact to provide a necessary component of the gun firing electric circuit. The device will open the electric contact when the gun recoils or when the loader so desires. The device provides a pivoted lever to close the electric contacts and reciprocating trip link means to alternately hold and release the biased lever.

The principal object of the present invention is to provide a sturdy device whereby the man loading the gun must move a lever to a fire position before the gun can be fired, and whereby the lever returns to a safe position automatically when the gun is fired so that the gun cannot be fired again.

Another object is to provide the loader with means to return the lever from fire position to safe position at any time.

The above and other objects of the invention will appear more clearly from the following more detailed description and from the drawing, wherein like numerals designate like parts in both figures.

FIGURE 1 is a perspective view of the left rear portion of a 105 mm. gun showing the loader's safety switch assembly in position on the gun.

FIGURE 2 is a detail of the loader's safety switch assembly viewed from the breech side of FIGURE 1.

The following detailed description of the preferred embodiment will be more clearly understood by first noting that an electric circuit, not shown, is closed to fire the gun provided that the loader's safety switch is closed. Such circuits are known per se and therefore need not be illustrated. It is sufficient here to state that the gun is fired electrically and that inserted in series with the electric

2

circuit, by means of leads 1, is a switch 2 shown in FIGURE 2. Switch 2 is closed when the button 3 is depressed thereby completing the electric circuit from a power source, not shown, to the firing switch, not shown. When both the firing relay switch, not shown, and switch 2 are closed electric power is delivered to detonate the load. FIGURE 1 shows lever 4 in the safe position wherein switch 2 is open and the gun cannot be fired. FIGURE 2 shows lever 4 in the fire position wherein switch 2 is closed and the gun may be fired.

FIG. 1 shows cradle 6 that slidably supports barrel 7 and breech 8 which is provided with breech block 9. The loader's safety switch assembly indicated generally at 10, is secured to gun cradle 6 by three bolts 11. Breech 8 recoils to the right relative to cradle 6. Boss 12 is fixed to breech 8 and reciprocates with the breech relative to cradle 6.

Slide link 5 is provided with an arm 13 extending in front of boss 12 so that boss 12 may push the arm 13 toward the front or restrain the arm 13 from moving toward the rear as will be explained below. As best viewed in FIGURE 2, base plate 14 of assembly 10 supports lever 4, slide link 5, and switch 2. Lever 4 is provided with a handle 15, a pin 16 secured to the lever, and adjustable bolt 17 secured to the lever. Slide link 5 is provided with elongated slots 18 and 19, a pivot pin 20 fixed to the slide link, and arm 13 extending toward the breech. Trip link 21 is provided with a handle 22, a boss 23, a hole to accept pivot pin 20, a front edge 24 and a rear edge 25 that extend down into the path of pin 16. Trip link 21 is pivotally secured to slide link 5 by pivot pin 20 and rests on the top of slide link 5 by means of trip link boss 23. Trip link 21 is urged clockwise in FIGURE 2 by gravity but may be assisted by spring means, not shown, acting between the slide link 5 and the trip link 21. Plate 14 is provided with fixed pins 26 and 27. Slide link 5 is slidably secured to plate 14 by pins 26 and 27 in slots 18 and 19 of the slide link. Lever 4 is rotatably secured to plate 14 by a standoff pivot 28 and pin 16. The inner end of pin 16 is fixed to the lever and the outer end is laterally restrained in arcuate slot 29 providing an exposed shank of pin 16 for engagement with trip link edges 24 and 25. Lever 4 is urged counter clockwise in FIGURE 2 by tension spring 30 attached between the lever and plate 14. Adjustable bolt 17 is secured on lever 4 to depress button 3 when lever 4 is in the fire position.

The operation of the device will be described by starting with the lever in the safe position which is shown in outline in FIGURE 2.

When the loader is prepared for the gun to be fired by the gunner he moves the lever 4 to the fire position. Boss 12 (FIGURE 1) always holds slide link 5 in the forward position except during a recoil. Pin 16 strikes edge 25 and rotates the trip link so that pin 16 slides under edge 25 and is trapped by edge 24 falling behind it. Lever 4 now holds bolt 17 in a position whereby bolt 17 depresses button 3 and switch 2 is thereby closed to add its required component to the firing circuit, not shown, by means of lead wires 1. If the loader desires to move the lever back to the safe position, he lifts handle 22 allowing pin 16 to escape along arcuate slot 29.

When lever 4 is in the fire position and the gun is fired, boss 12 recoils to the rear. Spring 30 acting through lever 4 and pin 16 urges edge 24 to the rear. The trip link 21 therefore, by the interaction between the pivot 20 and the boss 23 causes slide link 5 to follow boss 12 to the rear. Pin 16 moving down on the arcuate path escapes under edge 24 before slide link 5 is pushed forward by boss 12 on the forward stroke of the recoil.

While I have shown a new and improved loader's safety switch in combination with a gun I do not desire to be restricted to the exact structure described as many

modifications would be apparent to those skilled in the art.

I claim:

1. An electro-mechanical switch comprising, a base plate, a lever pivotally secured to said base plate, an electric switch actuated by said lever, a slide link slidably engaging said base plate, and a trip link supported by said slide link to hold said lever in switching actuating position. 10
2. Apparatus in combination with an electrically fired gun having a fixed member and a recoiling member comprising switch means to open and close part of the firing circuit, lever means to actuate said switch means, biasing means to continuously urge the lever to not 15 actuate said switch means, latching means cooperating with said recoiling member to hold said lever means in a switch means actuating position, support means for said switch means, lever means, and 20 latching means secured to said fixed member.

3. Apparatus as set forth in claim 2 wherein said lever means pivots about one end and carries latch engaging means in an arcuate path.

4. Apparatus is set forth in claim 2 wherein said latch- 5 ing means comprises a sliding member provided with an arm for engagement with said recoiling member, whereby said sliding member reciprocates on said support by co-operation of said lever means, said biasing means and said recoiling member.
